United States Patent Office

Des. 210,216
Patented Feb. 20, 1968

210,216

DOCUMENT CONVERTER

Robert V. Mallory, Kendall Park, N.J., assignor to International Business Machines Corporation, Armonk, N.Y., a corporation of New York

Filed Oct. 14, 1966, Ser. No. 4,279

Term of patent 14 years

(Cl. D26—5)

FIG. 1

FIG. 2

FIG. 3

FIG. 4

FIG. 5

FIG. 6

FIG. 1 is a front perspective view of a document converter showing my new design.

FIG. 2 is a front elevational view thereof.

FIG. 3 is an elevational view taken from the left side thereof.

FIG. 4 is an elevational view taken from the right side thereof.

FIG. 5 is a top plan view thereof.

FIG. 6 is a rear elevational view thereof.

The broken line representation of paper in FIG. 1 is for purposes of illustration only.

I claim:

The ornamental design for a document converter, as shown and described.
